UNITED STATES PATENT OFFICE

139,117

DESIGN FOR A DRESS

Margot Kops McClintock, Solebury, Pa.

Application August 25, 1944, Serial No. 115,021

Term of patent 3½ years

(Cl. D3—26)

To all whom it may concern:

Be it known that I, Margot Kops McClintock, a citizen of the United States, residing in Solebury, in the county of Bucks and State of Pennsylvania, have invented a new, original, and ornamental Design for a Dress, of which the following is a specification, reference being had to the accompanying drawing, forming part thereof.

Fig. 2 is a rear view of Figure 1.

I claim:

The ornamental design for a dress, substantially as shown.

MARGOT KOPS MCCLINTOCK.
